(57) **CLAIM**

The ornamental design for a stimulation device, as shown and described.

DESCRIPTION

FIG. 1 is a front elevation of a first embodiment of a stimulation device showing the design;

FIG. 2 is a top plan view of the stimulation device of FIG. 1;

FIG. 3 is a right side elevation of the stimulation device of FIG. 1;

FIG. 4 is a perspective view taken from the front and right side of the stimulation device of FIG. 1;

FIG. 5 is a perspective view taken from the top, front and left side of the stimulation device of FIG. 1;

FIG. 6 is a front elevation of a second embodiment of a stimulation device showing the design; and,

FIG. 7 is a perspective view taken from the top, front and left side of the body of the stimulation device of FIG. 6.

The right side elevation of the stimulation device of FIG. 6 is identical to FIG. 3.

A perspective view taken from the front and right side of the stimulation device of FIG. 6 at an angle corresponding to the angle of the perspective view of FIG. 4 is identical to FIG. 4.
